UNITED STATES PATENT OFFICE

IRVING KEMP, OF NEW YORK, N. Y., ASSIGNOR, BY MESNE ASSIGNMENTS, TO KEMP LOCK INC., OF NEW YORK, N. Y., A CORPORATION OF NEW YORK

LOCK

Application filed August 9, 1930. Serial No. 474,110.

This invention relates to locks. It is directed to the type of lock generally described in my co-pending application Serial No. 395,783, filed September 28th, 1929, 5 wherein a plurality of bolts are projected in a plurality of directions.

Among the objects of this invention is to generally improve the construction of locks of this character, so as to provide a neat, 10 compact and rugged structure, highly practical and efficient, comprised of few and simple parts, easily and quickly assembled, and which shall yet be smooth and positive in operation and practical and efficient to 15 a high degree.

Other objects of this invention will in part be obvious and in part hereinafter pointed out.

Certain features described in my co-pending application Serial No. 395,783, filed September 28th, 1929, including a plurality of U-shaped bolts adapted to be moved inwardly toward each other simultaneously with the projection of the horizontal bolt, 25 are shown and described, but not claimed in the present application.

With the foregoing exception, the invention accordingly consists in the features of construction, combinations of elements, and 30 arrangement of parts which will be exemplified in the construction hereinafter described, and of which the scope of application will be indicated in the following claims.

In the accompanying drawings, in which 35 are shown one of the various possible illustrative embodiments of this invention,

Fig. 1 is an elevational view of a lock embodying the invention with the rear cover removed therefrom, and showing the position of the parts when in locking position.

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1, with the lock in open position;

Fig. 5 is a view similar to Fig. 1, but showing a modified construction of a lock embodying the invention;

Fig. 6 is a side elevational view of the structure shown in Fig. 5;

Fig. 7 is a cross-sectional view taken on line 7—7 of Fig. 5; and

Fig. 8 is a partial detailed view of a portion of the horizontal bolt. 55

Referring now in detail to the drawings, 10 designates a door having a vertical edge 12 extending adjacent the door jamb 13 when said door is in closed position. Attached to the door adjacent said edge 12 is a lock 14 comprising in general, a casing 15 carrying a pair of U-shaped bolts 18 and 19 and a horizontal bolt 20 having projecting portions 21 and 22 adapted to engage as hereinafter described, a strike 23 attached to the door jamb 13. The casing 15 comprises a front wall 25, upper and lower walls 26 and 27 and end walls 28 and 29. The casing may be provided with any suitable means as for instance, ears 26a and 27a suitably bored for receiving screws for securing the casing to the door. Said casing 15 may be provided with any suitable guide means for slidably mounting the horizontal 70 bolt 20. A rear backing plate 30 removably secured to the casing in any suitable manner, is adapted to press against the inner or rear face of the bolt for retaining the same in position within the casing. 75

For reciprocating the said horizontal bolt 20, the front wall 25 of the casing is provided with a boss 31 bored as at 32 for rotatably receiving a knob 33. Fixedly attached to said knob 33 is one end of a crank 35 arm 34, the opposite end of which is formed with an opening 35 for rotatably receiving one end 36 of a curved link or connecting member 37. The latter may be downwardly curved as at 37—a, the opposite end 38 thereof being provided with a pin 39 pivotally engaging a suitable bearing opening in the horizontal bolt 20. 80

It will now be understood that rotation of the knob 33 will cause movement of the arm 34 and connecting member 37 for translating the bolt 20. 95

For actuation of the bolt 20 from the outside of the door, as for instance by use of a key, the crank arm 40 is pivotally mounted 100

on the rear plate 30 and provided with means not shown, adapted to cooperate with a key for turning said arm. Said arm 40 is provided with a cylindrical projection or 5 pin 41 rotatably received in the socket portion 42 integrally formed at one end of the connecting arm 37.

The casing 15 is provided with a vertical transverse, integral wall portion 45 parallel 10 to and spaced from said end wall 28. Said end wall 28 is formed with a pair of symmetrically disposed, spaced openings 47 and 48, and said wall 45 is provided with a pair of openings 47a and 48a aligned with said 15 openings 47 and 48 respectively. Fixed to the horizontal bolt 20 adjacent the ends thereof, are a pair of pins or bolt portions 47b and 48b adapted to slidably extend thru the openings 47, 47a and 48, 48a respectively. The strike 23 is provided with a pair of members 50 and 51 formed with 20 openings 50a and 51a adapted to receive the forward ends of said bolt portions 47b and 48b respectively.

Upon actuation of the knob 33 or key mechanism, the horizontal bolt 20 will be moved forwardly for projecting pins or bolt portions 47b and 48b into engagement with said strike portions 50 and 51, respectively.

Means is provided for moving the U-shaped bolts 18 and 19 inwardly toward one another, simultaneously with the projection of the horizontal bolt portions 47b and 48b. 35 To this end, said casing walls 45 and 28 are each provided with a pair of bearing openings 55, 56 respectively, said openings being preferably aligned and symmetrically disposed with respect to the mid-section of the 40 casing and disposed inwardly of the openings 47, 48 and 47a, 48a. Extending thru the aligned openings 55 is a rod 60 having a steep pitched helical thread 61 formed on the rear portion 62 thereof. Mounted on 45 the portion 64 of said rod, disposed between said walls 28 and 45 and suitably splined to said rod portion, as for instance in the manner hereinafter described, is a small gear wheel 65 substantially abutting 50 the end wall 28 and having a width smaller than the width of the space between said walls 28, 45. Extending from said gear wheel 65 is a hub or flange 66 adapted to contact said wall and fixed to said rod as 55 by means of a set screw 67. It will now be understood that the rod 60 is rotatably, but non-slidably mounted within the aligned bearing openings 55. The horizontal bolt 20 is provided with a suitable opening 70 slidably receiving the rear threaded portion of 60 the rod. A pin 71 screwed to said bolt 20 is provided with a projection or lug 72 adapted to extend into the helical groove formed on said rod, whereby upon movement of the horizontal bolt, coaction of the 65

lug 72 within the helical groove on said rod will cause rotation of the latter and accompanying rotation of the gear wheel 65.

Rotatably received within said aligned bearing openings 56 is a small stub shaft 70 75 73. Mounted on said shaft and suitably splined thereto is a gear wheel 74 substantially similar to said gear wheel 65, the former wheel being likewise smaller in width than the distance separating the walls 45 80 and 28. Gear wheels 65 and 74 are wider than one-half of the distance separating said walls 28 and 45, whereby said wheels are adapted to overlap and mesh with one another. Preferably integrally formed with 85 and extending from said gear wheel 74 is a hub or flange 75 contacting said end wall 28 and fixed to said shaft as for instance, by means of a set screw 76. Sliding movement of the gear wheel 74 and stub shaft 73 is 90 thus prevented. Said gear wheel 74 will be rotated upon actuation of the horizontal bolt 20 due to the meshing engagement with the gear wheel 65.

The casing 15 is provided with a pair of 95 aligned oppositely extending tubular portions 80 and 81 preferably square in cross-section adapted to slidably receive the arms 82 and 83 of said U-shaped bolts 18 and 19, respectively. The arm 82 of said bolt 18 is formed with a rack portion 84 having gear teeth 85 adapted to engage the teeth of the gear wheel 65. The rack portion 84 is substantially the width of the hub 75 and is hence disposed between the gear 74 and the 100 end wall 28. Upon actuation of the horizontal bolt 20 the gear teeth 85 will be engaged by teeth of the gear wheel 65 for moving the bolt 18. Such movement is permitted by reason of the construction of the 105 rack portion 84 of such width, that the same is received between the gear wheel 74 and the end wall 28, whereby said rack does not mesh with or engage said gear wheel 74. The arm 83 of the U-shaped bolt 19 is likewise provided with a rack portion 88 having a width substantially equal to the width of the hub 66 and being aligned therewith, said 110 rack portion having teeth 89 engaging the teeth of the gear wheel 74.

Thus, the rack portion 88 may be reciprocated without interference or engagement with gear wheel 65. Upon actuation of the knob, the gear wheels 65 and 74 will be rotated in opposite directions and hence the 115 U-shaped bolts reciprocated in opposite direction. The direction of the helical thread 61 and rod 60 is preferably such that upon projection of the bolt portions 47b, 48b, from the casing, the U-shaped portions 18 and 19 will be moved inwardly toward one another.

The strike 23 is provided with integrally formed portions 94, 95 at the opposite ends thereof formed with openings 92, 93 adapted 120

125

130

to receive the preferably square-shaped arms 90, 91 of the U-shaped portions 18 and 19 respectively.

The lock may quickly and easily be as-

sembled or disassembled. Upon unscrewing or removal of the set screws 67, 76 and 71, the rod 60 and stub shaft 73 may be removed thru the end wall 28 of the casing. The gear wheels 65 and 74 and their respective 10 hubs 66 and 75 may then be easily removed, thus permitting further disassembly of the bolts 18 and 19. The bolt portions 21 and 22 obviously may also be detachably attached to the horizontal bolt 20 as for instance, by 15 forming said horizontal bolt with suitable bearing openings for receiving the inner ends of said bolt portions and providing suitable set screws for fixing said inner ends to said horizontal bolt.

20 In accordance with the modified construction shown in Figs. 5, 6, 7 and 8, means is provided for rotating the projecting portions of the horizontal bolt at the end of the projecting stroke for the purpose herein-

25 after described. To this end, a horizontal bolt 20a, substantially similar in construction to said bolt 20, is adapted to be translated by similar mechanism. Said bolt 20a is provided with a pair of bearing openings

30 100 and 101 adjacent the opposite ends thereof, and rotatably received within said bearing openings are parallel bolt portions 102 and 103 formed at the outer ends thereof with extensions or wings 104 and 105 re-

35 spectively. Said bolt portions are furthermore formed with longitudinal slots or grooves 106 and 107, respectively, and with annular grooves 108 and 109, respectively, communicating with said longitudinal slots

40 106 and 107, respectively. Each of said bolt portions 102 and 103 is furthermore formed with a pair of spaced outwardly projecting pins 110. It will be noted that the projections 110 on the bolt portion 102 are differ-

45 ently positioned longitudinally with respect thereto from the pins 110 on the bolt portion 103. Said pins 110 are so spaced on their respective bolt portions that when said bolt portions are in fully projected positions, as shown in Fig. 5 of the drawings, said projections will engage the respective rack portions 84a and 88a respectively (substantially similar to the rack portions 84 and 88 shown in Figs. 1 and 2).

55 The lock casing 15a is substantially similar to said casing 15. However, the end wall 28a of said casing 15a is substantially thicker than the corresponding wall 28 shown in Fig. 1. Said end wall 28a however, 60 is provided with openings 112, 113 adapted to receive the front ends of the bolt portions 102, 103, so that upon retracting the horizontal bolt in the manner hereinafter appearing, the forward ends of the bolt portions will fit into said openings. Fixed to

said end wall 28a are pins 115, 116 adapted to project into the longitudinal grooves 106 and 107 respectively, of the bolt portions 102 and 103.

The operation of the device will now be clear. The U-shaped bolts 18a and 19a are similar in construction to the bolts 18 and 19 and are similarly connected to the horizontal bolt.

Upon actuating the horizontal bolt 20a, for projecting the same, the bolts 102 and 103 will be slidably moved outwardly and the relative positions of the pins 115 and 116 within the longitudinal grooves 106 and 107 will be changed.

Near the end of the stroke, the pins 115 and 116 will become aligned with the annular grooves 108 and 109.

At this point in the projection of the horizontal bolt, the outwardly extending pins or projections 110 will engage the teeth of the inwardly moving racks 84a and 88a

35 respectively, so that the bolt portions 102 and 103 will be given a rotary movement in addition to the forward movement out of the casing. The rotary movement will bring the wings 104 and 105 from a position trans-

verse to the lock to a position parallel thereto as shown in Fig. 5 of the drawings. The parts are preferably so proportioned that the bolt portions 102, 103 will be given a rotary movement of 90°.

The strike 23a is provided with integral portions 120 and 121 having transverse openings 122 and 123 respectively, large enough to admit the front ends of the bolt portions therethru. When said front ends of the bolt portions have been

50 passed entirely thru the openings 122 and 123 of the strike portions 120 and 121 respectively, the rotary movement of said bolt portions begins, and the wings 104 and 105 are then brought into the positions shown in

55 Figs. 5 and 6 of the drawings. The lock is thus rendered jimmy-proof and the bolt portions 102 and 103 cannot be given a sliding retracting movement without proper actuation of the knob 33 or key mechanism, be-

60 cause of the inter-engagement of the wings 104 and 105 and strike portions 120 and 121. Obviously, upon retracting the horizontal bolt rotary movement is given to the bolt

65 portions 102 and 103 by reason of the inter-engagement of the projecting pins 110 with the respective rack portions 84a and 88a, which are moved outwardly by the gear

70 wheels. When the wings 104 and 105 are brought to the transverse position for align-

75 ment with said openings 122 and 123, the pins 110 will come out of engagement with the rack teeth and the pins 115 and 116 will enter the longitudinal grooves 106 and 107.

The remainder of the retracting movement 80 will then cause only sliding movement of the bolt portions 102 and 103. It will be noted that rotation of the bolt portions 102 and 103 is not possible until the pins 106 and 107

are aligned with the annular grooves 108 and 109 respectively.

The helically grooved rods, as well as the remainder of the actuating mechanism, are located within the casing, and only the bolts are projected, this construction making for a neat and compact lock.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

20 Having thus described my invention, what I claim as new and desire to secure by Letters Patent, is:—

1. A lock comprising a casing, a member formed with a helical thread rotatably and 25 non-slidably mounted within said casing, and a bolt slidably mounted within said casing adapted to be projected from said casing, having means coacting with the thread of said member for causing rotation thereof upon slidably moving said bolt, and a second bolt slidably mounted on said casing for movement in a direction transverse to the direction of movement of said bolt, and means on said member operatively engaging said second bolt for moving the same upon causing sliding movement of said first bolt.

2. A lock comprising a casing, a member having a helical thread thereon non-slidably and rotatably mounted within said casing, 40 a gear wheel mounted on said member for rotation therewith, a second gear wheel meshing with said first wheel mounted for rotation within said casing, a pair of oppositely extending bolts having rack portions 45 meshing with said gear wheels, and a member slidably mounted within said casing having means coacting with the thread of said first member for causing rotation thereof.

3. A lock comprising a casing, a member 50 having a helical thread thereon non-slidably and rotatably mounted within said casing, a gear wheel mounted on said member for rotation therewith, a second gear wheel meshing with said first wheel mounted for 55 rotation within said casing and a pair of oppositely extending bolts having rack portions meshing with said gear wheels, a member slidably mounted within said casing having means coacting with the thread of said first member for causing rotation thereof, said last named member having a portion 60 adapted to be projected from said casing.

4. In a lock, a casing having a pair of 65 parallel wall portions formed with two pair of aligned bearing openings, a rod rotatably

mounted in one pair of openings having a portion extending beyond one of said walls, a shaft rotatably mounted in the other pair of aligned openings, a gear wheel mounted on said rod and between said walls, and a second gear wheel mounted on said shaft meshing with said first gear wheel.

5. In a lock, a casing having a pair of parallel wall portions formed with two pair of aligned bearing openings, a rod rotatably 75 mounted in one pair of openings having a portion extending beyond one of said walls, a shaft rotatably mounted in the other pair of aligned openings, a gear wheel mounted on said rod and between said walls, a second gear wheel mounted on said shaft meshing with said first gear wheel, and a pair of oppositely extending rack members meshing with said gear wheels.

6. In a lock, a casing having a pair of parallel wall portions formed with two pair of aligned bearing openings, a rod rotatably 80 mounted in one pair of openings having a portion extending beyond one of said walls, said rod being formed with a helical thread, 90 a shaft rotatably mounted in the other pair of aligned openings, a gear wheel mounted on said rod and between said walls, a second gear wheel mounted on said shaft meshing with said first gear wheel, a pair of oppositely extending rack members meshing with 95 said gear wheels, and a horizontal bolt slidably mounted within said casing having a portion extending into the threaded groove on said first rod, and means for translating said horizontal bolt for rotating said rod and said gear wheels.

7. In a lock, a casing, a member having a helical thread rotatably and non-slidably mounted therein, a member slidably mounted within said casing having a projection extending into the threaded groove of said first member, a gear wheel fixed to said first member, a bolt having a rack meshing with said gear wheel, said slidably mounted member having a bolt portion adapted to be projected from said casing and means on said bolt portion adapted to mesh with said rack for causing rotation of said bolt portion simultaneously with the projecting movement thereof.

8. In a lock, a casing having a pair of parallel wall portions, formed with a pair of aligned bearing openings, a rod rotatably 105 mounted within said openings and having a portion extending beyond one of said walls, said rod being formed with a steep pitched helical thread, a member slidably mounted within said casing having a portion projecting into the thread of said rod for causing 110 rotation thereof, a geared wheel mounted on the portion of the rod extending between said walls and splined to said rod, a horizontal bolt portion on said slidably mounted member, and a vertical bolt having a rack 115

120
125
130

portion meshing with said gear wheel whereby said bolt portion and bolt may be simultaneously projected.

9. In a lock, a casing, a member rotatably and non-slidably mounted therein, a member slidably mounted within said casing having means co-operating with said first member to cause rotation thereof, a gear wheel fixed to said first member, a bolt having a rack meshing with said gear wheel, said slidably mounted member having a bolt portion adapted to be projected from said casing, and means on said bolt portion adapted to engage said rack for causing rotation of said bolt portion simultaneously with the projecting movement thereof.

10. A lock comprising a casing, a member having a helical thread thereon non-slidably and rotatably mounted within said casing, a bolt slidably mounted within said casing having a projection engaging said thread for rotating said member upon causing sliding movement of said bolt, a gear wheel mounted on said member for rotation therewith, a second gear wheel meshing with said first wheel mounted for rotation within said casing, and a pair of oppositely extending bolts having rack portions meshing with said gear wheels, said gear wheels being similar in size and mounted on aligned, parallel axes, and said rack portions being aligned and parallel.

11. A lock comprising a casing, a member formed with a helical thread rotatably and non-slidably mounted within said casing, a bolt slidably mounted within said casing having a portion adapted to be projected from said casing, said bolt being provided with means coacting with the thread of said member for causing rotation thereof upon slidably moving said bolt, a hand knob rotatably mounted on said casing, and means connecting said knob to said bolt for causing sliding movement of the latter upon rotating the former.

12. A lock comprising a casing, a member having a helical thread thereon rotatably and non-slidably mounted within said casing, means for rotating said member including a bolt slidably mounted in said casing and having a portion engaging said thread, and means for causing sliding movement of said bolt, a gear wheel fixedly mounted on said member, and a second bolt mounted on said casing for sliding movement in a direction transverse to the movement of the first bolt and having a rack meshing with said gear wheel.

13. A lock comprising a casing, a member having a helical thread thereon rotatably and non-slidably mounted within said casing, a bolt slidably mounted in said casing and having a portion adapted to be projected therefrom, said bolt having a projection engaging said thread, means for causing

sliding movement of said bolt for rotating said member, a gear wheel fixedly mounted on said member for rotation therewith, a second gear wheel rotatably mounted within said casing and meshing with said first wheel, and a pair of oppositely extending bolts having racked portions meshing with said gear wheels.

In testimony whereof I affix my signature.

IRVING KEMP.
